CIGAR MAKING MACHINE

Constantin Friedrich Röber and Ernst Röthig,
Dresden, Germany, assignors, by mesne assignments,
to J. C. Muller N. V., Rotterdam, Netherlands

Application April 13, 1938, Serial No. 201,772
In Germany May 15, 1937

10 Claims. (Cl. 131—30)

This invention relates to cigar making machines, and more particularly to a means in combination with a wrapping machine for firmly holding the end of the wrapper first applied to the filler in a manner so that the first end of the wrapper will readily adapt itself to the configuration of the filler.

At the present time in the making of cigars by machines the wrapper is carried to a position for engagement with the filler by a suction carrier, the construction of which is well known, and the wrapper is then removed from the carrier and the free end started on an end of the filler. The removal of the wrapper from the carrier is accomplished by means of a resilient finger which not only removes the initial or starting end of the wrapper from the carrier, but also applies this end of the wrapper onto the end of the filler. Due to the varying configuration of the cigar ends difficulty is experienced at the present time in snugly applying the starting end of the wrapper on the filler, and it is, therefore, an object of this invention to provide a wrapper applying means which can be used with varying types of cigar ends and which irrespective of the configuration of the end of the cigar filler will snugly and firmly apply the starting end of the wrapper on the filler.

It is also an object of this invention to provide a wrapper applying means which is so constructed that it can be accurately timed in its operation with the filler mechanism so that the cigar production can proceed at a relatively rapid rate.

With the foregoing and other objects in view, the invention will be more fully described hereinafter, and will be more particularly pointed out in the claims appended hereto.

In the drawings, wherein like symbols refer to like or corresponding parts throughout the several views:

Figure 1 is a fragmentary detail side elevation of a cigar filler having a rounded or blunt end and showing a resilient finger for applying the wrapper thereto.

Figure 2 is a view similar to Fig. 1, but showing a filler having a tapered or conical end.

Figure 3 is a fragmentary side elevation of a wrapping machine having a wrapper starting device constructed according to an embodiment of this invention combined therewith.

Figure 4 is a detail end elevation of the structure shown in Fig. 3.

Figure 5 is a top plan of the structure shown in Fig. 4.

Figure 6 is a detail view of the parts operating finger 26 of Figure 3.

Figure 7 is a like view but with the feeding finger pressed down further and folding the end of the wrapper thereabout.

Figure 8 is a similar view but with the finger in its lowermost position in the wrapping socket and with the end of the wrapper in contact with the cigar filler.

Figure 9 is a detail side elevation of the operating mechanism for the tucking needle.

Referring to the drawings, and first to Figs. 3 to 8 inclusive, the numeral 1 designates a pair of rollers known as filler rollers, but it will be understood that additional rollers 40 are used to engage about the filler W for the purpose of tightly wrapping the wrapper D thereabout.

The rollers 1 are secured to shafts 1a which are journaled in bearings 2 and 3 carried by the frame structure 21. Spur gears 4 are fixed to the shafts 1a adjacent the bearing 3 and mesh with a relatively large spur gear 5 secured to a countershaft 6. A smaller spur gear 7 is fixed to the shaft 6 and meshes with a driving gear 8 which is fixed to a drive shaft 9 connected to a suitable source of power.

The frame 21 is provided with an outstanding arm 20, and a lever 15 is pivotally mounted on this arm 20 by means of a pin 19 which engages the lever 15 between the ends thereof. The upper end of the arm 15 is provided with a recess 16, Figure 6, in which a bar 12 engages, and this bar 12 is adjustably held in the recess 16 by means of a bolt 17 extending through an elongated slot 18 in the arm 15. The slot 18 is disposed substantially parallel with the axes of the shafts 1a so that the adjustment of the bar 12 may be made longitudinally of the shafts 1a and the rollers 1.

A socket generally designated as 10 is mounted on or secured to an arm 11 which is provided with a slot 14 adjacent the lower end thereof, and the arm 11 is adjustably secured to the bar 12 by means of a bolt 13. In this manner the arm 11 may be adjusted vertically so as to properly position the socket 10 with respect to the end Sp of the filler W. The socket 10 is preferably open on its upper side, as at 29 so that the end E of the wrapper D may enter the socket, and at one side of the opening 29 an upstanding flange 28 is provided. A resilient finger 26 is adapted to engage in the opening 29, pressing the wrapper through the opening 29 and onto the end Sp of the filler W positioned within the socket 10.

The wrapper D is positioned over the filler rolls 1 by means of a movable carrier 25 the operating features of which are well known and not believed necessary to illustrate. The carrier 25 is provided in its under surface with a downwardly opening slot 27 in which the finger 26 is adapted to engage so as to be positioned on the upper side of the wrapper D.

The socket 10 is rocked toward and away from the filler W by means of a disc 24 which is fixed to the drive shaft 9 and which is provided with a cam flange 23. The lower end of the lever 15 is provided with a roller 22 which engages the cam 23, and a spring 21a yieldingly holds the roller 22 in contact with the cam 23, one end of the spring 21a being secured to a part of the frame 21 and the other end of the spring 21a being secured to the lower end of the lever 15.

The spring finger 26 may be mounted on a suitable part of the frame 21, engaging in a slot 3a provided between the bearings 3, and this finger 26 is normally biased to an uppermost position as shown in full lines in Fig. 3. With reference to Figure 9, the tucking needle 26 is swung down against the end of the wrapper E by a rod 41 pivoted on the end of an arm 42 which has its lower end pivoted in a bracket 43 and which carries a crank roller 44. A spring 45 on the bracket 43 engages the arm 42 and holds the roller 44 yieldingly against the periphery of a disc 46 driven through gears 47 from the shaft 9. The disc 46 has a cam or raised portion 48 on its periphery which engages the roller 44 and swings the arm 42 and the rod 41 toward the needle 26, as shown in dotted lines in Figure 9. Spaced stops 49 on the needle engage the eye of the rod 41 and move the needle back and forth with the rod 41. The needle passes through the top of the frame 3 and the forward stop 49 tapers to engage the frame and tilt the needle 26 downwardly, as shown in Figure 9 in dotted lines.

In the use and operation of this device, the carrier 25 is swung to a position where an end of the wrapper D overlies the socket 10 when the socket is in operative position, or in the position shown in full lines in Fig. 3. The finger 26 is so positioned that the swinging of the carrier 25 to a discharging position will also cause the end of the finger 26 to enter the slot 27 above the wrapper D. The finger 26 is then swung downwardly and as the finger 26 engages the wrapper D inwardly of the adjacent end thereof the downward swinging of the finger 26 will bend the free end of the wrapper D as shown in Figs. 6 and 7, the end of the wrapper D sliding down along the surface 30 of the flange 28. The filler W at this time is rotating in the direction of the arrows shown in Figs. 6, 7 and 8, and as the bent end of the wrapper D passes downwardly through the opening 29 and contacts with the filler in the socket 10 both the wrapper D and the finger 26 are drawn into the socket 10 as shown more clearly in Fig. 8 with the bent portion of the wrapper folded about the finger 26. The finger 26 makes a complete revolution within the socket 10 and is bent to the configuration of the socket 10 by pressure of the socket 10 against the end S₀ of the filler W. After one revolution of the filler and finger 26 in the socket 10 the finger 26 is displaced longitudinally toward the left of Fig. 3 by its operating mechanism shown in Fig. 9.

When the wrapper D is completely disposed about the filler W the cam 23 will swing the socket 10 to a released position, shown in dotted lines in Fig. 3. The completed cigar may then be removed

from the rollers 1 and a new filler inserted and the operation repeated. By means of the adjustable mounting for the socket 10, the axis of this socket may be finely adjusted with respect to the axis of the filler W, and the longitudinal adjustment of the bar 12 will permit the positioning of the socket 10 in a manner to firmly press against the adjacent end of the filler W. The detachability of the socket 10 will permit the use of any desired socket configuration, and the use of a resilient finger 26 will permit the use of any desired socket without changing the other parts of the device, as the finger 26 will readily adapt itself to any socket configuration. The longitudinal adjustment of the socket 10 with respect to the rollers 1 will also permit the use of this structure with any length of filler, so that a wrapping machine equipped with this invention may be used with cigars of different configurations and sizes both as to diameter and length.

It will be apparent from the foregoing that the starting end of the wrapper will be firmly and snugly held against the end of the filler, irrespective of the configuration of the adjacent end of the filler, as the pressure of the socket 10 against the end of the filler W is sufficient to effect a bending of the finger 26 coincident with the shape of the socket 10.

It is obvious that various changes and modifications may be made in the details of construction and design of the above specifically described embodiment of this invention without departing from the spirit thereof, such changes and modifications being restricted only by the scope of the following claims.

What is claimed is:

1. In combination with a cigar wrapping structure including filler rollers and a wrapper transferring means, means engageable with an adjacent end of the wrapper on said transferring means, for releasing the wrapper from the transferring means, a socket, means supporting said socket for movement toward and away from said filler rollers, and means carried by said socket for engagement with said releasing means whereby said releasing means may enter said socket with the adjacent end of the wrapper.

2. In combination with a cigar wrapping structure including a plurality of filler rollers, a wrapper carrier and a vertically movable wrapper releasing member, a socket engageable with an end of the filler disposed between said filler rollers, means supporting said socket for swinging movement toward and away from said rollers, means for swinging said socket toward and away from said rollers, and means carried by said socket for guiding said releasing means thereinto upon downward movement of said releasing means.

3. In a cigar wrapping means including filler rollers, a wrapper carrier and a releasing means for releasing the wrapper from said carrier, a socket engageable with an end of the filler disposed between said filler rollers, means supporting said socket for swinging movement toward and away from said rollers, cam means for swinging said socket, and means carried by said socket for guiding said releasing means thereinto upon downward movement of said releasing means.

4. In a cigar wrapping means including filler rollers, a wrapper carrier and a vertically swingable wrapper releasing means, a socket engageable with an end of the filler disposed between said filler rollers, a rock lever, means securing said socket to said lever, means for rocking said

lever whereby to swing said socket toward or away from a filler disposed between said filler rollers, and means carried by said socket for guiding said releasing means thereinto upon downward movement of said releasing means.

5. In a cigar wrapping means including filler rollers, a wrapper carrier and a vertically swingable wrapper releasing means; a socket engageable with an end of the filler disposed between said filler rollers, a rock lever, means securing said socket to said lever in a manner whereby said socket may be adjusted relative to the filler engaged between said rollers, means for rocking said lever whereby to swing said socket toward or away from a filler disposed between said filler rollers, and means carried by said socket for guiding said releasing means thereinto upon downward movement of said releasing means.

6. In a cigar wrapping machine, a filler receiving socket having a slot at one side, means for turning the filler in the socket, means for delivering a wrapper with one end adjacent the slot, a tucking needle, and means for operating the needle to engage the end of the wrapper and insert the same in said slot against the forward end of the filler for turning therewith to wind the wrapper about the filler during the turning of the same in the socket.

7. In a cigar wrapping machine, a socket adapted to fit over the end of a filler and having a slot in its side with an outstanding flange at one side of the slot, means for feeding the wrapper with one end adjacent the slot in the socket, a tucking needle, and means for operating the tucking needle for moving the same against the said end portion of the wrapper and wiping the wrapper against said flange to overturn the wrapper on the needle, said operating means being adapted to move the needle into said slot and socket for applying the end of the wrapper to the filler.

8. In a cigar wrapping machine, a nest of rollers disposed in circular form for supporting a filler, a socket, means for adjustably supporting the socket at one end of said rollers to engage the end of the filler and said socket having a slot in its upper side with a guiding flange extending outwardly from one edge of the slot, means for

delivering a wrapper with one end adjacent the slot in the socket, a tucking needle, means for operating the tucking needle for engaging the end of the wrapper and tucking the same downwardly against said flange and through the slot into the socket for engagement with the end of the filler, and means for operating said rollers to turn the filler therebetween and in the socket to wind the wrapper thereabout.

9. In a cigar wrapping machine, a plurality of rollers arranged in circular order to provide a support for a filler, a socket disposed at one end of the rollers for engaging the end of the filler and provided with a slot in one side and a radial flange at one edge of the slot, means for turning the rollers to rotate the filler therebetween and in the socket, a wrapper delivering device adapted to dispose a wrapper with one end over the slot in said socket, a tucking needle, operating means for the needle to engage the same with the end of the wrapper and wipe the same downwardly against said flange through the slot in the socket and into contact with the filler, whereby the filler during rotation is adapted to entrain the end of the wrapper and draw the same through said slot and between the rollers for wrapping the filler, and means for automatically retracting the filler socket from the end of the wrapped filler at the end of each wrapping operation.

10. In a cigar wrapping machine, rotatable supporting means for a filler adapted to rotate the filler to facilitate wrapping, an end socket for the filler, an arm movably mounted adjacent the socket, a connecting member positioned between said arm and socket, means between the connecting member and socket to provide perpendicular adjustment of the latter relating to the filler axis, means between the connecting member and arm to provide longitudinal adjustment of the socket in respect of the filler, and operating means for said arm adapted to cause intermittent angular displacement of the socket from the filler without affecting the subsequent coincidence of said socket and subsequent filler.

CONSTANTIN FRIEDRICH RÖBER.
ERNST RÖTHIG.
